UNITED STATES PATENT OFFICE

ALBERT E. GARBUT, OF WINNIPEG, DONALD COCHRANE, OF ST. BONIFACE, AND JOHN E. WATKINS, OF WINNIPEG, MANITOBA, CANADA, ASSIGNORS TO WINNIPEG BRASS LIMITED, OF WINNIPEG, CANADA, A CORPORATION OF MANITOBA, CANADA

ANNUNCIATOR

Application filed June 18, 1928, Serial No. 286,181, and in Canada, June 15, 1928.

The invention relates to improvements in annunciators and an object of the invention is to provide an annunciator particularly valuable for use on street cars and such like 5 public conveyances and which is specially designed to indicate route numbers and is arranged so that the one in charge can readily change the number as and when desired.

A further object of the invention is to construct the device so that it can be conveniently mounted on the exterior of the vehicle in an exposed position and such that the operator can set or change the route numbers by manipulating hand cranks positioned in a convenient location within the vehicle.

A further object is to construct the device in a simple, durable and inexpensive manner and such that the various parts can be readily assembled or taken apart for inspection or 20 other purposes.

A further object is to provide means for maintaining the belts taut at all times.

A still further object is to provide a simply constructed crank control for winding the 25 belts in either direction and also to provide a simple means whereby the operator can determine when the numbers on the belts are properly located.

A further object is to construct the device 30 so it can be readily put in place from the interior of the vehicle and such that the entire device can be easily released and drawn into the vehicle as and when desired.

With the above more important and other 35 minor objects in view which will become more apparent as the description proceeds, the invention consists essentially in the arrangement and construction of parts hereinafter more particularly described, reference being 40 had to the accompanying drawings, in which:—

Fig. 1 is a perspective view of the complete device.

Fig. 2 is an enlarged detailed vertical longitudinal sectional view at 2—2' Figure 4.

Fig. 3 is a horizontal sectional view at 3—3' Figure 2.

Fig. 4 is a vertical sectional view at 4—4' Figure 2.

Fig. 5 is an enlarged detailed vertical sec-

tional view through certain of the working parts, portions thereof being broken away.

Fig. 6 is a vertical sectional view at 6—6' Figure 7.

Fig. 7 is an enlarged detailed vertical sectional view through the inner end of one of the upper rollers.

Fig. 8 is an enlarged detailed vertical sectional view at 8—8' Figure 2.

Fig. 9 is a perspective view of one of the bearing brackets.

Fig. 10 is a perspective view of the indicating pointer.

Fig. 11 is an enlarged detailed inverted plan view of the pocketed sleeve.

Fig. 12 is a plan view of the upper end of the crank.

Fig. 13 is an enlarged detailed face view of the pointers and adjacent belts.

In the drawings like characters of reference indicate corresponding parts in the several figures.

The box or casing 1 containing the belts and parts associated therewith is substantially rectangular and is preferably formed from 75 sheet metal and has both the front and rear sides thereof closed by rectangular frames 3 and 4 fastened thereto by screws 5 and containing transparent plates 6 and 7 such as of glass. An attaching plate 8 is fastened to the bottom of the box and extends beyond the ends thereof and is provided with suitable screw or bolt holes 9 for fastening the device to the conveyance.

In the four corners of the box and to the 85 rear side thereof, we secure permanently similar brackets 10, 11, 12 and 13 which provide vertically disposed bearing sleeves 14 and horizontally disposed bearing sleeves 15. The bearing sleeves 15 of the brackets 10 and 11 are transversely aligned as are also those 15 of the upper brackets 12 and 13 and the bearing sleeves 14 of the brackets 10 and 12 are vertically aligned as are those bearings 14 of the brackets 11 and 13. 95 Centrally to the rear of the box, we permanently secure also similar upper and lower bearing brackets 16 and 17 which have their inner ends forked to provide receiving bearings 18, the upper bearing 18 being axially 100

aligned with the upper bearing sleeves 15 and the lower bearing 18 being axially aligned with the lower bearing sleeves 15.

It will be apparent that we have six bearings and such bearings are utilized to rotatably support upper and lower pairs of shafts 19 and 20, the inner ends of the shafts being carried by the bearings 18 and the outer ends by the bearings 15. The outer ends of the shafts are all reduced as indicated at 21 to enter the bearings 15 and the inner ends of the shafts are retained within the bearings 18 by cotter pins 22. On the shafts, we mount rotatably upper and lower pairs of rollers 23 and 24, these rollers being formed from opposing end heads 25 and 26 connected together by a tube or pipe 27 of predetermined length. The pairs of rollers carry belts 28 and 29.

In order to fasten the ends of the belts to the rollers or winding drums in a simple and effective manner, we have provided the ends of the belts with hems 30 and have passed a retaining rod 31 into each hem. The tubes 27 are longitudinally slotted as indicated at 32 to permit the ends of the belts to pass therethrough but the width of the slot in each instance is less than the diameter of the rod so that the rod cannot pull out through the slot.

In order to enter the rods, we have made holes 33 in the inner heads of the winding drums. When the belts are to be fastened to the drums, the hemmed ends thereof are passed through the slots and brought into a position aligned with the holes 33. One then passes the rods through the holes and into the hem, the rod being pushed in until it is free of the head at which time, it will drop down and serve as an anchor retaining the hem from withdrawing through the slot.

To the outer heads of the drums, we secure by screws bevel pinions 34 and these pinions of the upper and lower drums are continuously in mesh with upper and lower bevel gears 35 and 36 mounted on similar vertically disposed winding shafts 37 and 38. Each of the latter shafts has its upper end contracted to provide a shoulder 39 and a spindle 40 thereabove, the spindle 40 being rotatably received in the upper bearing sleeves 14 and also carrying rotatably the upper gear wheel 35 which is supported by the shoulder 39. A cross pin 41 passes through the upper end of the spindle and a wearing washer 42 is placed between the pin and the upper end of the upper sleeve 14, this holding the shaft against escaping.

Each of the shafts 37 and 38 passes downwardly through the bottom of the box and the ends of the shafts projecting from the box are enclosed within pipes or tubes 43 and 44, said pipes having their upper ends screw threaded into bosses 45 fastened to the under side of the plate 9 and their lower ends screw threaded to receive a bearing sleeve 46.

The lower end of each shaft 37 or 38 as the case may be passes rotatably through the bearing sleeve 46 and has fastened thereto the head 47 of a crank 48 which is provided with a hand grip 49. A jam screw 50 fastens the head of the crank to the shaft.

The under face of the bearing sleeve is provided with a plurality of equi-spaced semi-circular pockets 51 and there is preferably an odd number of these pockets. The upper face of the head 47 is drilled to provide two diametrically opposite pockets 52 and 53 which receive springs 54 and catches 55 in the form of balls. The upper ends of the drilled pockets 52 and 53 are struck in to prevent the balls from escaping from the pockets but it will here be observed that there is sufficient of the ball permitted to protrude from the pocket under the pressure of the spring to form a compressible catch engageable with one or other of the pockets 51.

By having the balls 55 diametrically opposite and an odd number of pockets 51, we obtain a relatively fine adjustment of the head 47 in regard to the sleeve 46, as one ball will enter one of the pockets to prevent undesired rotation of the head 47 and the other ball will be riding the face of the sleeve 46 between the pockets thereof. Obviously the turning of the crank controls the rotation of the shaft 37 or 38 as the case may be and the shaft will be releasably locked in any desired position by the entrance of one or other of the balls in one or other of the pockets 51.

The gear wheels 36 hereinbefore mentioned are both permanently fastened by pins 56 to the shafts 37 and 38 so that the lower winding drums are positively driven by the shafts. The upper bevel gears 35, however, are rotatably mounted on the spindles of the shafts and the only driving connection between the shafts and the upper bevel gears is by way of coiled springs 57 and 58 mounted on the shafts and having their lower ends permanently fastened at 59 to the shafts and their upper ends permanently fastened at 60 to the upper bevel gears 35.

These springs turn the bevel gears 35 when the shafts are turned and serve to compensate for the gradual variation in the diameters of the winding and unwinding ends of the belts as will be readily understood.

The belts are provided throughout their length with the numbers 0123456789 appearing in arithmetical progression throughout the length of the belts, the numbers being placed thereon in any suitable manner. We find it desirable to have the belts made from a black flexible material and the numbers appearing thereon in white so that there is a sharp contrast. The belts are made so that they move close to the glass or window 7 through which the numbers thereon must be clearly visible and in this connection,

might point out that when the device is in use, only one number on each belt should be seen at one time. In Figure 1, we have shown in dotted outline the numbers 3—8 as appearing through the window 7 and these numbers indicate the route number 38.

The inner edges of the belts are guarded by a vertical strip 61 which can be also painted black and this strip carries a centrally located vertically disposed plate 62 which extends vertically between the bearings 18 and is utilized to carry similar pointed indicators 63 and 64. The indicators are both fastened by a bolt 65 to the plate, the bolt passing through a suitable hole provided in the plate and elongated slots 66 in the bases of the indicators. This arrangement allows either of the indicators to be adjusted vertically in respect to the adjacent belt. The belts are both provided at their inner edges and on their rear faces with stop marks 67 selectively positioned in respect to the adjacent belt numbers. We have considered it desirable to use small numbers on the belts as stop numbers, the small number corresponding in each instance to the adjoining large number.

In order that the motorman or other operator may be able to properly set the annunciator without leaving the car vestibule, we have provided a transparent peep opening 68 in the roof of the car through which the motorman can see the indicating pointers and the stop marks and obviously if he wants to set the belts to indicate the route number 38, he will turn the respective belts until he sees the small stop numbers 38 positioned opposite the pointers at which time he knows that the route number is properly positioned in respect to the window 7.

In placing this device on say the front end of a street car vestibule, a substantially rectangular hole 69 is cut in the roof of the vestibule and this hole permits the box to be passed upwardly therethrough until the projecting ends of the plate 8 strike the under side of the roof. The roof carries bolts 70 and 71 which are adapted to pass into the bolt openings 9 of the plate and the whole device is held in place by winged nuts 73 screwed up against the ends of the plate. This arrangement makes it very convenient not only to put the device in place but also to dismount it from the car at any time. The cranks 48 and 49 are located within convenient range of the motorman and the whole arrangement is such that he does not require to leave his usual position in the vestibule in order to see and set the belts.

The glass plates 6 and 7 forming the windows are held between resilient strips 74 and 75 so that there will be no rattling and such that the interior of the casing will be dust proof and weather proof.

What we claim as our invention is:—

1. In an annunciator, in combination, a

pair of upper and lower rotatably mounted drums, a belt connecting the drums, a rotatably mounted winding shaft, bevel pinions secured to the ends of the drums, bevel gears carried by the shaft and meshing with the pinions, one of said gears being fixed to the shaft and the other being rotatable thereon and a yielding driving connection between the shaft and the latter bevel gear. 70

2. In an annunciator, in combination, a pair of upper and lower rotatably mounted drums, a belt connecting the drums, a rotatably mounted winding shaft, bevel pinions secured to the ends of the drums, bevel gears carried by the shaft and meshing with the pinions, one of said gears being fixed to the shaft and the other being rotatable thereon and a coiled spring carried by the shaft and having one end fastened thereto and the other end fastened to the latter bevel gear. 75

3. In an annunciator, in combination, a hollow rotatably mounted drum having a lengthwise slot therein and an opening to the interior of the drum through one end thereof, the opening being offset in regard to the end of the slot, a belt having a hem at the end thereof, the hem entering the interior of the drum through the slot and an anchor rod contained in the hem within the drum, said rod being passed into the hem through the opening in the end of the drum and having a diameter greater than the width of the slot. 85

4. In an annunciator, a vertically disposed rotatably mounted drum winding shaft, a bearing sleeve rotatably receiving the shaft 100 and provided on the under side with an odd number of spaced pockets, a crank secured to the winding shaft and a pair of diametrically opposing spring pressed ball catches carried by the crank and engageable in the turning of the crank with the pockets. 105

5. In combination, a box like annunciator, an attaching plate secured to the base of the annunciator and extending beyond the ends thereof and provided at its ends with attaching openings and crank controlled annunciator winding shafts extending downwardly from the ends of the box. 110

6. In an annunciator, in combination, rotatably mounted drum carrying shafts, a belt connecting the drums, a rotatably mounted winding shaft, a direct driving connection between the winding shaft and one of the drum shafts and a yielding driving connection between the winding shaft and the other of the drum shafts, said yielding driving connection compensating for the variation in the diameter of the belt as it winds on and off the drums. 115

7. In an annunciator, in combination, rotatably mounted parallel drum carrying shafts, a belt connecting the drums, a rotatably mounted winding shaft, a driving member fixed to the winding shaft, a driving member rotatably mounted on the winding shaft, 120 125

4
driven members secured to the drums and driven by the former driving members and a yielding driving connection between the rotatably mounted driving member and the winding shaft.

- 5 6. In an annunciator, in combination, a pair of upper and lower rotatably mounted drums, a belt connecting the drums, a rotatably mounted winding shaft, bevel pinions secured to the ends of the drums, bevel gears carried by the shaft and meshing with the pinions, one of said gears being fixed to the shaft and the other being rotatable theron, a coiled spring carried by the shaft and having one end fastened thereto and the other end fastened to the latter bevel gear, exposed manually operated means for turning the winding shaft and means for releasably holding the winding shaft in any turned position.
- 10 15 20 Signed at Winnipeg, this 16th day of April, 1928.
